SPINNING MACHINE

Charles Bierman, Jr., Cincinnati, Ohio, assignor to The Cincinnati Milling Machine Co., Cincinnati, Ohio, a corporation of Ohio

Filed Dec. 20, 1955, Ser. No. 554,190

4 Claims. (Cl. 113—52)

This invention relates to forming machines and more particularly to new and useful improvements in a spinning machine for forming parts out of flat sheet metal on a shaping mandrel.

One of the objects of this invention is to provide a new and improved machine of the class described which is automatically operated.

Another object of this invention is to provide a rugged machine for spinning parts out of relatively heavy gage metal with precision and with a minimum of waste.

A further object of this invention is to provide a hydraulically operated machine having opposed spinning heads on opposite sides of a mandrel, and to accurately control their rate of feed to keep them in step so that each will do its equal share of work.

A still further object of this invention is to provide a spinning machine with opposed spinning heads and selective control means so that either one or both heads may be utilized.

An additional object of this invention is to simplify the construction of such machines and make them more readily adaptable to different conditions by providing individual tooling units that are universally adjustable on a flat bed so that they may be set to follow any taper without the use of templates or profiles.

Other objects and advantages of the present invention should be readily apparent by reference to the following specification, considered in conjunction with the accompanying drawings forming a part thereof, and it is to be understood that any modifications may be made in the exact structural details there shown and described, within the scope of the appended claims, without departing from or exceeding the spirit of the invention.

Referring to the drawings in which like reference numerals indicate like or similar parts:

Figure 1 is a plan view of a machine embodying the principles of this invention.

Figure 2 is a section on the line 2—2 of Figure 1.

Figure 3 is a section on the line 3—3 of Figure 1.

Figure 4 is a section on the line 4—4 of Figure 1.

Figure 5 is a detail section on the line 5—5 of Figure 4.

Figure 6 is a detail section on the line 6—6 of Figure 5.

Figure 7 is a detail section on the line 7—7 of Figure 2.

Figure 8 is a detail section on the line 8—8 of Figure 2.

Figure 9 is a detail section on the line 9—9 of Figure 1.

Figures 10, 11 and 12 are diagrams of the electrical control circuit.

Figure 13 is a diagram of the hydraulic control circuit.

Figure 14 is a diagrammatic view of the main slide selector switch.

Figure 15 is a diagrammatic view of the cross slide selector switch.

Figure 16 is a diagram of the control circuit for the headstock motor.

Referring to the drawings, and more particularly to Figures 1 and 2, the machine of this invention comprises in general a large bed plate 10 on a base 10' having mounted along a central axis thereof, a headstock 11 and

2

a tailstock 12 for supporting therebetween a tapered mandrel 13 upon which a work piece such as 14 is formed.

On the opposite sides of the mandrel and mounted on top of the bed are two similar self-contained tool units 15 and 16, the unit 15 being the rear unit and the unit 16 being the front unit. Each unit has a spinning tool 17 which is supported for rotation by the construction shown in Figure 5. Each tool unit is self-contained in that they have their own prime movers for the longitudinal feeding and cross feeding movements. Each unit, such as the unit 16, has a support or bed plate 18 which rests upon the top of the bed 10 and is adjustable thereon to arrange its working axes in suitable angular relation to the axis of rotation of the work so as to be parallel to the taper of the mandrel. To assist in this adjustment an adjusting screw 19 is threaded in a fixture 20 which is fastened to the top of the bed by T-bolts 21 mounted in a T-slot 22 formed on the top of the bed 10. The screw has an operating handle 23 and is connected by a ball joint 24 to a ball socket 25 secured to the plate 18. After adjustment, the unit is bolted to the top of the bed 10 by a series of T-bolts 26 mounted in suitable T-slots formed on top of the bed. The unit 15, although of opposite hand to the unit 16, also has a support or bed plate 27 which is secured to the bed 10 by suitable T-bolts and an adjusting mechanism indicated generally by the reference numeral 28 and, similar to the adjusting mechanism for the unit 16, is secured to the bed 10.

As shown in Figure 2, the headstock has a spindle 29 journaled therein and, due to the heavy forces involved, the headstock has a double conical anti-friction bearing 30 at the mandrel supporting end and an anti-friction bearing 31 at the other end, as well as an intermediate anti-friction thrust bearing 32 to absorb the end thrust 35 on the mandrel. The end of the spindle is connected by a coupling 33, Figure 1, to the output shaft 34 of a variable speed gear box 35. The input shaft 36 of the gear box is connected by a suitable motion transmitting mechanism 37 to a prime mover, such as an electric motor 38. The gear box may be any conventional gear selector box having a gear selector control lever 39 whereby the rate of rotation of the spindle may be changed relative to the motor. The spindle 29 has a face plate 42 secured by suitable bolts 41 to a flange 40 formed on the end of the spindle. The mandrel 13 which, of course, 45 may be of various sizes and tapers, is attached to the face plate 42 by suitable screws 43.

The headstock 11 is fixed to the bed of the machine, but the tailstock 12 is supported on suitable guides 44, as shown in Figure 7, for movement toward and from the end of the mandrel. This movement is effected hydraulically by a piston 45, as shown in Figure 2, contained in a cylinder 46 secured to the bed, and connected by a piston rod 47 to the depending bracket 48 of the tailstock 12.

55 The tailstock has a spindle 49 journaled therein on anti-friction bearings 50 and thrust bearing 51. This spindle has a chuck 52 mounted in the end thereof, and, as shown in Figure 8, comprises three adjustable jaws 53 and suitable radial adjusting screws 54 in which may be clamped a conical spider 55, which is interchangeable for various sizes of work. In operation, the tailstock is retracted with respect to the mandrel, a work piece blank, such as 14, mounted on a boss 56 formed on the end of the mandrel, and then the tailstock is brought into position to clamp the blank against the end of the mandrel by the spider and with sufficient friction so that the mandrel, blank, spider and tailstock spindle are power rotated by the headstock spindle.

70 The construction of each tool unit is the same, with the exception that one is of opposite hand to the other and therefore a description of one will suffice for both. The

rear unit 15, as shown in Figures 1, 3, and 4, has the support or bed plate 27 on which is formed guide surfaces 57, 58 and 59, as shown in Figure 4, it being noted that the vertical guide surface 59 is the one that takes the lateral thrust on the spinning roller 17. A longitudinally movable carriage or main slide 60 is formed and shaped to engage these surfaces and to be guided thereby. Hold-down gibs 61 and 62 are provided on each side of the units and suitably secured to support 27 to hold them in engagement with the surfaces 63 and 64 respectively of the slide 60. This slide is power reciprocated by a piston 65, Figure 3, contained in a cylinder 66 which is attached to the support 27, and the piston 65 is connected by a piston rod 67 by a suitable connection at 68 to the slide 60.

The main slide 60, in turn, carries a cross slide 69, as shown in Figure 4, slideable on suitable guide surfaces 70 formed on the supporting slide 60. Holddown gibs 71 and 72, Figure 3, are provided on opposite sides of the slide 69 in the conventional manner. The cross slide 69 is actuated by a piston 73 contained in a cylinder 74 which is mounted on a bracket 75 fixed with the slide 60. The piston 73 is connected by a piston rod 76 to the cross slide 69 for actuation thereof. The cross slide 69 has a tool head 77 which supports the spinning roller 17. This head is angularly adjustable about a pivot in the form of a bolt 78 which is threaded into a nut 79 fixed with the slide 69. Angular adjustment of the tool head is effected by a rack and pinion, the rack 80 being formed on the tool head 77, and the pinion 81 rotatably supported in engagement therewith on a stud 82 threaded in the slide 69. The gear is operatively connected to a handle 83 for manual rotatable adjustment thereof. The tool is clamped after adjustment by a pair of clamping bolts 84 which pass through elongated slots 85 and 86 as shown in Figure 1 and are threaded into the base of the slide 69. The spinning or forming roller 17 is mounted in a special bearing construction shown in Figures 5 and 6.

The end of the tool head 77 is bifurcated to form jaws 87 and 88, Figure 5, and a removable axial pin 89 is mounted in these jaws. The head 90 of the pin is held against rotation by a set screw 91 threaded in the head 77. The other end of the pin is provided with a large washer 92 and clamping bolt 93. Mounted on the pin 89 is a sleeve 94 having flanges 95 secured to each end and in which are mounted the inner races 96 of tapered roller bearings. The outer races 97 are mounted in suitable spaced relation in a ring 98. This ring has an annular groove or seat 99 for the roller 17, and the roller is held in the seat by a spring washer 100. When it is desired to change the roller 17, the axial pin 89 is removed and the entire assembly is taken out of the jaws 87 and 88 so that the spring washer 100 may be removed and the roller 17 slid off and replaced by another roller. This makes a simple construction for quickly changing the roller 17.

For normal operation, the support 27 of unit 15, as well as the support 18 of the unit 16, are aligned parallel to the taper on opposite sides of the mandrel and also longitudinally so that spinning tools are positioned to the left beyond the end of the mandrel and work. After the blank is loaded between the rollers and the end of the mandrel, the cross slides are advanced to some predetermined position as determined by a positive stop mechanism to determine the work thickness to be spun, because the rollers not only shape the work but also may reduce the thickness of the original blank. This mechanism is shown more particularly in Figure 9 and comprises a stop bolt 101 which is threaded into the cross slide 69 and locked in position by a locking set screw 102. The other end of the bolt passes freely through a hole 103 in the bracket 75 where it is provided with an adjustable rotatable nut 104 having graduations 105 formed on a flange 106. The flange abuts a hardened

ring 107 countersunk in the part 75 and thereby determines the limit of movement of the slide 69.

Summing up the operation of the machine thus far, it will be seen that for each new job the operator selects 5 the proper shape of mandrel and attaches it to the face plate of the headstock, and a suitable spider, such as 55, is attached to the tailstock in the manner described. The work piece, such as 14, is then inserted between the end 10 of the mandrel and the tailstock and manually supported in position while the tailstock is advanced to clamp the work blank against the end of the mandrel.

At this time the tool slides are arranged parallel to the taper on the corresponding sides of the mandrel, depending upon its conical angle, and the tool rollers are positioned 15 at the left of the end of the mandrel so that the work is inserted between the rollers and end of the mandrel, and, if necessary, the angular position of the tool holders is adjusted at this time.

It will be noted from Figure 5 that the periphery of 20 the spinning roller is a conical surface 17a, and that the large end of the cone terminates in a radius 17b adjacent one side face of the roller, forming a blunt nose which is the active working part of the tool or roller. The tapered surface thus forms a clearance which may be 25 adjustable depending on the angular adjustment of the tool head. There are various factors which may necessitate adjustment such as the taper angle of the mandrel, the type of material, and the amount that the blank is to be reduced in thickness to form the finished part.

The operator starts the headstock rotating and the cross 30 slides advance to position as determined by the positive stops. The stops determine the wall thickness of the finished product which is usually less than the thickness of the original work blank. In fact, the finished wall 35 thickness is utilized to determine the thickness of the blank stock from which it is to be formed. Normally, this is done by drawing two parallel lines a unit distance apart, as shown in Figure 2 at T, and computing the area of the oblique rectangle between the two lines on the 40 finished work and then making the square or rectangle between the two lines on the work stock equal to that same area. This will determine the thickness of the blank.

The longitudinal slides are started and the work spun 45 to the desired shape and wall thickness. Before returning the slides, the tailstock is retracted and the finished product removed so that it can be done without interference from the rollers. After the work piece has been removed, the longitudinal slides are returned to starting 50 position and the next blank is inserted in the machine.

The power operating mechanism for the machine is 55 illustrated in the form of a hydraulic control circuit shown in Figure 13, and the pilot controls for the various actuating solenoids are governed by an electric control circuit 55 shown in Figure 10, and the pilot controls are governed by an electric control circuit shown in Figures 11 and 12. Each of the operating cylinders previously described have their own reversing valve and a solenoid operated pilot valve for effecting power shifting of the associated reversing valve. The various solenoids and the switches 60 which effect their operation are shown in Figure 10. All of these switches or contacts are parts of relays found in Figures 11 and 12.

Although means have been provided for individual 65 actuation or jogging of a particular slide which can be designated as manual control, the full operation of the machine is termed herein as automatic cycle operation. A selector switch 108 has been provided as shown in Figure 11 for selecting one or the other type of operation. 70 This switch 108, when operated to select manual control, interconnects contacts 109 and 110 to complete a circuit from the power main 211 to line 111 which is connected in parallel to relays 12CRA and 12CRB and then to the common return power line 102.

For the purpose of easily locating the various elements

in the electrical control circuit it will be noted that the power lines 211 and 102 extend through the circuits shown in Figures 10, 11, and 12, and they derive their power from the secondary 112 of a supply transformer indicated generally by the reference numeral 113. The reference line E1 has been run parallel with the whole circuit, and each across-the-line sub-circuit from power line 211 to line 102 has been indicated by reference characters on the line E1.

To set the circuit up for automatic cycle operation which will be described first and in which it will be assumed that both main slides and cross slides of the tooling units will be operated simultaneously, the selector switch 108 is positioned to close contacts 114 and 115 in line E27 to effect simultaneous operation of relays 13CRA and 13CRB.

Since an interlock has been provided between the tailstock and the cross slides to insure that the tools are not moved into engagement with the work until it is clamped by the tailstock, a selector switch 116 has been provided for closing contacts 117 and 118 in line E33 if the interlock is not desired, or for closing contacts 119 and 120 in line E34 if the interlock is desired. The operation of the machine will be described utilizing the interlock in which case the selector switch 116 will be positioned to close the contacts 119 and 120 in series with the pressure switch 2PS and cycle start control relay 14CR in line E33.

There are two other selector switches shown diagrammatically in Figures 14 and 15 having three positions whereby the front tool slide or the rear tool slide may be selected for individual operation or both tool slides may be selected for simultaneous operation. The main slide selector switch is indicated generally by the reference numerals 121 in line E36, the details of which are shown in Figure 14 and the cross slide selector switch is indicated generally by the reference numeral 122 in line E49, the details of which are shown in Figure 15. As shown in Figure 14, the switch 121 has three series of contact pads which may be rotatably positioned to close different groups of switches in accordance with the slide or slides to be operated. For operation of both slides, the pads 123, 124, 125, and 125' shown in Figure 14 are rotated into position so that the pad 123 interconnects contacts 126 and 127, pad 124 interconnects contacts 128 and 129, pad 125 interconnects contacts 130 and 131, and pad 125' interconnects contacts 130' and 131'. To facilitate the description, these sets of contacts have been indicated as closed in Figure 11 in lines E39, E42, E44, and E46 respectively.

Similarly, the switch 122 is provided with four switch pads for operation of both cross slides simultaneously, the switch pads 132, 133, 134, and 135 are rotated in position so that pad 132 interconnects contacts 136 and 137, 133 interconnects contacts 138 and 139, pad 134 interconnects contacts 140 and 141 and pad 135 interconnects contacts 142 and 143. For convenience, these contacts are shown as closed in lines E50, E53, E55, and E57 in Figure 12.

Having made these selections, the operator clamps the work blank in the machine by operating the tailstock advance push button 144 which closes contacts 145 and 146 in line E59 and thereby energizes relay 10CR. This relay closes its latching contact 10CR-1 in line E60 to latch in the relay so that the push button may be released. The relay also opens switch 10CR-3 in line E-61 to break the circuit to tailstock reverse control relay 9CR. As shown in Figure 10, line E15, switch 10CR-2 is also closed by the relay to energize solenoid 10. Referring to the hydraulic diagram, Figure 13, solenoid 10 shifts the pilot valve plunger 147 to the left because all of the solenoids shown in this figure are of the push type. The pilot valve 147 controls the power shifting of the reversing valve 148 for the tailstock actuating piston 45.

The reversing valve has a pressure port 149 supplied by pump 150, and this port is in the form of an annular

groove whereby the pressure will continue through channel 151 to pressure port 152 of pilot valve 147. Therefore, when the plunger 147 is shifted to the left, the pressure port 152 will be connected to channel 153 and shift the reversing valve plunger 148 to the left against the resistance of centering spring 154. This will introduce pressure from port 149 to channel 155 and thereby to the end of cylinder 46 to advance the tailstock into work clamping position. When the tailstock has completed its movement the pressure in the end of cylinder 46 will build up to a maximum pressure and effect operation of the pressure switch 2PS. This pressure switch, shown in line E34, Figure 11, will close and complete a circuit to the relay 14CR in E33. This relay may now be energized by closing the cycle start button 156. The circuit to this switch was established by the closing of selector switch 13CRA-1 (E33), the normally closed stop button 159 and timer relay switch 4TR-2. The relay 13CRA also closed contacts 13CRA-2 in line E38, 13CRA-3 in line E43, 13CRA-4 in line E49, 13CRA-5 in line E55 and since relay 13CRB was simultaneously operated at that time, contacts 13CRB-1 in line E60 and 13CRB-2 in line E63 were also closed. Thus, the operator by actuating the push button 156 will close contacts 157 and 158 to energize relay 14CR and close its latching contacts 14CR-1 in line E35 around the starting switch, as well as closing contact 14CR-2 in line E36.

The closing of switch 14CR-2, E36, connects power from line 211 to line 211B through closed contact 13CRA-1, cycle stop switch 159, closed contact 14CR-1 and line 160 so that power is now supplied to the closed switches 13CRA-4 in line E49, Figure 12, and 13CRA-5 in line E-55. The limit switches 4LS and 2LS shown in E49 are carried by the longitudinal slides and are held closed by suitable dogs when these slides are in their starting position, while their corresponding switches 4LS-1, E41, and 2LS-1, E46, are held open. Therefore, the circuit is now complete to contacts 136 and 138 in lines E-50 and E-53, and these are connected by the selector switch 122 to contacts 137 and 139 respectively whereby cross slide control relays 8CR and 5CR are energized to start the advance of the cross slides toward the work.

As shown in Figure 10, these relays will close switches 5CR-1 in line E8 and 8CR-1 in line E13 and thereby energize solenoids SOL5 and SOL8. These relays will open normally closed contacts 8CR-2, E51 and 5CR-2, E57 to prevent operation of control relays 6CR and 7CR. Also, cross slide limit switches 6LS (E57) and 7LS (E51) are held open by dogs in their starting position and as soon as the slides move away from the dogs, the limit switches will close. Referring to Figure 13, solenoid 5 pushes the pilot valve plunger 161 to the right, thereby connecting its pressure port 162 to port 163 and thereby, through channel 164, cause shifting to the right of the reverse valve plunger 165 associated with the cross slide 69. The pressure port 162 is supplied by a pump 166 through pressure reducing valve 167, lines 168 and 169, and the annular pressure port groove 170 of the reversing valve and channel 171. When the reverse valve plunger is shifted to the right, the pressure groove 170 is connected to channel 172 and thereby to one end of the cylinder 74 to advance the cross slide 69 to the limit of its movement.

Similarly, the solenoid 8 shifts the pilot valve plunger 173 to the left and connects pressure port 174 to channel 175, thereby shifting the reverse valve plunger 176 associated with the cross slide 69' whereby pressure is connected from the pressure port 177 of the reverse valve through the throttle valve 178 and line 179 to shift the cross slide 69' to the limit of its movement. Thus, both cross slides move simultaneously to advance the tools to working position. The cross slide 69 has limit switches 5LS and 6LS associated therewith and when the slide is advanced, limit switch 6LS in E57 assumes a normally

closed position, while its other contacts 6LS-1 in E63 assume a normally open position. Similarly, when the cross slide 69' advances, it releases limit switch 7LS in E51 which closes while 7LS-1 in E63 opens. The limit switches 8LS and 5LS shown in line E38 of Figure 11 will be dog closed at the end of cross slide advance and connect switch 13CRA-2 to the contacts 126 and 128 in lines E39 and E42 respectively to start the longitudinal slides 60 and 60'. These contacts have been connected by the selector switch 121 to contacts 127 and 129 whereby control relays 3CR and 1CR in lines E38 and E42 will be energized. It will be seen from Figure 10 that relays 1CR and 3CR will close switches 1CR-1 and 3CR-1 in lines E4 and E6 respectively and thereby energize solenoids SOL-1 and SOL-3. They will also open switches 1CR-2, E46 and 3CR-2, E41, preventing operation of relays 2CR and 4CR, when limit switches 2LS and 4LS-1 close as the main slides begin to advance.

Referring again to Figure 13, solenoid SOL-1 will shift the pilot valve plunger 180 to the right connecting pressure port 181 to line 182 and thereby to the left end of the reversing valve plunger 183 associated with the longitudinal slide 60. This plunger will connect the pressure port 184 to channel 185 and thereby to the end of cylinder 66 to advance the longitudinal slide 60. In the same manner the solenoid SOL-3 will shift the pilot valve plunger 186 to the left and connect pressure port 187 to line 188 and thereby shift the reversing valve plunger 189 associated with the longitudinal slide 60' to the left whereby fluid pressure from the pressure port 190 will flow through line 191 and advance the longitudinal slide 60'. When these two slides advance, they will release limit switches 2LS-1 (E46) and 4LS-1 (E41) associated therewith, which will close, but switches 1CR-2 and 3CR-2 are open, whereby control relays 2CR and 4CR are prevented from operating; and at the end of their travel will open switches 1LS-1 and 3LS-1 respectively, in lines E42 and E38 respectively, deenergizing relays 1CR and 3CR. At the same time this will close limit switches 1LS-2 and 3LS-2 in line E55 and complete the circuit from closed switch 13CRA-5 to contacts 140 and 142. These contacts are connected by 141 and 143 respectively to control relays 6CR and 7CR in lines E57 and E51 respectively.

This deenergizes solenoids SOL-1 and SOL-3 whereby the reversing valves 183 and 189 are returned to a central position because all of the reversing valves are spring held in a central position as by springs 191 and 192. Therefore, the main slides will stop and remain in that position. However, the limit switches have closed contacts 1LS-2 and 3LS-2 in line E55 and complete a circuit from closed switch 13CRA-5 to switch contacts 140 and 142 which are connected to contacts 141 and 143, thereby energizing relays 6CR and 7CR. It is to be noted that contacts 1CRB and 3CRB in line 48, which were closed during the traversing movement of the main slides, are now open thereby deenergizing relays 5CR and 8CR so as to close their contacts 8CR-2 (E51) and 5CR-2 (E57). This will energize solenoids SOL6 and SOL7 and cause return movement of the cross slides whereby limit switches 5LS and 8LS will be released and limit switches 6LS and 7LS will be operated when the cross slides have completed their movement. Release of limit switches 8LS and 5LS in line E38 will open the circuit to main slide control relays CR1 and CR3. Operation of limit switches 6LS and 7LS will open the circuit to cross slide control relays 7CR and 6CR in lines E51 and E57 and close the circuit to timer relay 4TR in line E63, closing switch 4TR-1 in line E43. The relays 6CR and 7CR will deenergize solenoids SOL6 and SOL7 whereby the reversing valves for the cross slides will return to neutral position, and the slides will stop in their outward position.

At this point the operator effects retraction of the tailstock by operating the push button 193 in line E59, closing contacts 194 and 195 in line E61 to energize relay

9CR. This will close contact 9CR-1 in line E14 to energize solenoid SOL9 and close latching contacts 9CR-2, E62. This solenoid will shift the pilot valve 147 to the right, causing shifting of the reverse valve 148 to the right, and pressure will be connected to channel 196 and cause return movement of piston 45 connected to the tailstock. Completion of return movement of the tailstock will operate limit switch 9LS in line E61 which will break the circuit to relay 9CR and thereby deenergize solenoid SOL-9 whereupon the reversing valve 148 will return to a central position.

The parts are now in a position for the operator to remove the finished work piece from the mandrel. When this is completed, he operates the main slide return push button 197 in line E41 and thereby closes contacts 198 and 199 in line E43 to complete a circuit through 13CRA-3 and closed timer switch 4TR-1 to switch contacts 130 and 130' in lines E44 and E46 respectively. Since the limit switches 2LS-1 and 4LS-1 are normally closed at this time, control relays 2CR and 4CR will be operated to energize solenoids SOL2 and SOL4 which will operate the reversing valves 183 and 189 to cause the main slides to return to starting position. In doing so, they will open limit switches 2LS-1 and 4LS-1 whereby they will break the circuit to control relays 2CR and 4CR and stop the return movement. The parts are now back in a starting position so that the operator may load the next work blank.

Attention is invited to the fact that in order to equalize the load on each of the spinning tools so that each will do its share of the work, the main longitudinal slides must be maintained in step even though they are hydraulically operated. This is accomplished in the present invention by providing mechanism for maintaining the back pressure in each of the main slide operating cylinders 66 and 66' equal throughout their stroke. The mechanism for doing this includes two balancing valves shown in Figure 13 and indicated generally by the reference numerals 200 and 201. The return channel 202 from cylinder 66, which terminates in port 203 of the reversing valve 183, is connected to port 204 during the working stroke of the slide 60. This port is connected by channel 205 to port 206 of a rapid traverse control valve indicated generally by the reference numeral 207. The hydraulic shifting of the valve plunger 208 of this valve is controlled by a pilot valve indicated generally by the reference numeral 209 and having a plunger 210 which is actuatable by solenoid SOL-14 shown at E30 in Figure 11.

Normally, these two valves are in the position shown in Figure 13 whereby the return fluid from cylinder 66 is directed by way of valve groove 211 in plunger 208 to port 212 and thus by way of channel 213 to the throttled port 214 of balancing valve 200. At the same time the pressure in groove 211 is directed through channel 215, interconnected ports 216 and 217 of valve 209, channel 218 to cylinder 219 to maintain the valve plunger 208 in its shifted right position. The pressure in channel 213 is also directed through branch channel 220 and choke coil 221 to the left end of valve 200 whereby the pressure plus a spring 222 maintains the balancing valve plunger 223 constantly urged toward the right to uncover the port 214. The port 214 causes a pressure drop in the fluid passing therethrough, and this fluid continues through the valve groove 224, channel 225 and a low pressure throttle valve 226 to a scavenger pump 227 which is continuously acting to draw fluid from channel 228 and return it to the reservoir 229.

The fluid returning from cylinder 66' passes through the same type of circuit including channel 230 to reversing valve 189 and thence by return channel 231 to a rapid traverse control valve 232, the operation of which is governed by a pilot valve 233 operated by solenoid SOL-16. With the valves in their normal position as shown in Figure 13, the fluid from channel 231 is di-

rected to channel 234 and throttle port 235 of the other balancing valve 201. The fluid pressure in channel 235 is directed through channel 236, branch channel 237 and choke coil 238 to the left end of valve 201 whereby the pressure plus a spring 239 urges the valve plunger to the right to uncover port 235. An exhaust channel 240 from this valve is connected by a throttle valve 241 to a return channel 242 which eventually is connected to channel 228 and pump 227.

In order to balance the position of the plungers in the respective balancing valves they are cross connected so that the back pressure in one cylinder is balanced against the back pressure in the other cylinder. In other words, the channel 220 which conducts fluid to the left end of valve 200 also has a connection through choke coil 243 to the right hand end of balancing valve 201. Similarly, the channel 236 which receives the back pressure from cylinder 66' is connected by a choke coil 244 to the right hand end of balancing valve 200. It will now be seen that with respect to balancing valve 200 that the valve plunger thereof is balanced between the back pressure of one cylinder 66 against the back pressure from the other cylinder 66' so that if the back pressure in cylinder 66 should rise above the back pressure in cylinder 66', the plunger 223 would be urged toward the right to reduce the throttling at port 214 and thereby relieve the pressure in cylinder 66 while, at the same time, this same higher pressure would act on balancing valve 201 to urge the plunger thereof to the left and increase the resistance of port 235 and thereby raise the back pressure in cylinder 66'.

Similarly, if the back pressure in cylinder 66' should rise above that in cylinder 66, the plunger in balancing valve 201 would be shifted to the right to relieve the pressure in cylinder 66 and also act to shift the plunger 223 in balancing valve 200 to the left to increase the resistance of port 214 and raise the pressure in cylinder 66'. Thus, the back pressure in each feeding cylinder reacts on the other to maintain both of them substantially constant. Thus, the feed rate of one is balanced against the feed rate of the other to maintain the movement of each spinning roller in step and under equal load so that each does its proportionate share of the work.

The rapid traverse valves have been provided to effect fast movement of the longitudinal slides as for set-up purposes, and such movements are effected under manual control. As shown in Figure 11, the solenoids SOL-14, E30, and SOL-16, E32, are connected to a rapid traverse pushbutton control switch 245 in E32 by way of switches 1CRB-1 and 3CRB-1 respectively.

The rapid traversing movement is effected in the case of SOL14 by the shifting of the pilot valve 210 to the left, causing the shifting of the valve plunger 208 to the left. Port 206 now becomes connected to port 246, which is connected by channel 247 directly to the return channel 242, thus bypassing the balancing valve 200 and connected throttle valve 226.

Similarly, valve plunger 248 of rapid traverse pilot valve 233 is shifted to the left by SOL16, causing shifting of plunger 249 to the left and connecting return line 231 directly to return line 242, bypassing balancing valve 201 and its connected throttle valve 241.

It will be noted that since only switches 1CRB-1 and 3CRB-1 are provided in the circuit to the solenoids, and operated by relays 1CR and 3CR, rapid traverse of the longitudinal slides can only be obtained in one direction, mainly, in the advance direction of the slides.

As previously set forth, the selector switch 108 may be positioned for manual control at which time relays 12CRA and 12CRB, E25 and E26 respectively, will be energized and relays 13CRA and 13CRB will be deenergized. This will close switches 12CRA-1, E37, 12CRA-2, E41, 12CRA-3, E51, 12CRA-4, E54, 12CRB-1, E59, and 12CRA-4', E42. This will set up two branch manual control circuits in parallel with the

two automatic control circuits. With the closing of switches 12CRA-2 and 12CRA-4', the power line 211 is connected for manual control of the four control relays for the main slides.

- 5 In line E41 there is shown serially connected the main slide advance push button 248, return slide pushbutton 249, jog stop switch 250 and a timer relay switch 1TR-1. With all of these switches closed, the push button 248 may be closed to energize the advance control relays 1CR and 3CR simultaneously if the main slide selector switch 121 is in its center position, as shown, for control of both sides. When this happens, switch 1CR-4 and 3CR-4, E42, will close and latch in the circuit. It is during this time that the rapid transverse may be effected. The slides will thus continue to move until the stop button 250 is operated which breaks the circuit to the two control relays to insure against reoperation should the button be released quickly. The stop switch 250 is provided with a second switch 251 which closes a circuit to timer relay 1TR in E47. This will open its contact 1TR-1 in E41 immediately, but it has a timed closing so as to insure that the latching switches 1CR-4 and 3CR-4 are opened and thereby positively break the circuit to the control relays.
- 10 Should it be desired to manually control the other two relays 2CR and 4CR to effect simultaneous return movement, the pushbutton 249 is operated which completes a circuit through 12CRA-4', because 13CRA-3 is open, and close contacts 198 and 199 in E43 and upon operation of these two relays they will close their latching switches 2CRA-2 in line E44 and 4CR-2 in line E-45. This movement may be stopped at any time by actuation of the stop switch 250 which will through the timer relay 1TR prevent reoperation.
- 15 It will be noted that when the advance switch 248 is closed that it has a second contact 252 which opens the circuit to the reverse control relays to prevent simultaneous operation of all four relays.
- 20 As previously mentioned, the rapid advance pushbutton 245, E32, controls operation of the rapid traverse valves, but the direction control valves associated therewith have to be operated also in order that the rapid traverse valves will be effective. Therefore, the switch 245 is provided with a second contactor 253, E45 which is simultaneously operated by the push button to complete a circuit around the advance pushbutton 248 which is normally open in order to energize either one or both of the control relays 1CR and 3CR. Whatever relays are operated, dependent upon the position of selector switch 121, the corresponding switches 1CRB-1, E30, and 3CRB-1, E32, associated with relays 1CRB and 3CRB connected in parallel with relays 1CR and 3CR respectively will be selectively closed, thereby effecting operation of one or both of solenoids SOL14 and SOL16. Stoppage of this rapid movement is effected by stop button 250 in E41.

The same general method of manual control operation applies to the cross slides. In E51 the switch 12CRA-3 is closed upon selection of manual operation which thereby completes the circuit through serially connected timer contacts 2TR-1, stop switch 254, return switch 255, and the advance switch 256. Closing of the advance switch 256 completes a circuit to contacts 136 and 138 in lines E50 and E53 of drum selector switch 122 which determines whether either or both of these contacts will be connected to contacts 137 and 139 respectively. One or both of relays 5CR and 8CR will thus be operated to shift either of the corresponding control valves and simultaneously close latching contacts 5CR in E52 and/or 8CR in line E53.

70 Stoppage is effected by operating pushbutton 254 which has a second contact at 257 in line E58 to operate timer relay 2TR which immediately opens switch 2TR-1 in line E51 and time closes to insure that the latching switches 75 will open in case of quick release of the push button.

To effect return movement of the cross slides the push-button switch 255 is operated, which interconnects contacts 258 and 259 in E52 to complete a circuit to cross slide reverse control relays 6CR and 7CR or whichever one is selected by the selector switch 122. Stoppage is also effected in this case by push button 254 in the same manner. The relays 6CR and 7CR have latching contacts 6CR-1 and 7CR-1 in lines E53 and E54 and the circuit to these will be broken by the timer relay contacts 2TR-1 in line E51.

The control circuit for the headstock motor is shown at the bottom of Figure 12 and comprises a pilot circuit 260 having serially connected start and stop switches 261 and 262 respectively which control operation of relay 18CR. This relay has a latching contact 18CR-1 in line E66 for maintaining the relay closed upon release of the start button. The relay 18CR has a second contact 18CR-2 in a control circuit for the headstock motor, and a selector switch 263 is provided in connection therewith and has three positions, the center position being the off position. If the switch is moved to close contacts 264 and 265 the circuit is completed to switch 18CR-2 for continuous operation, or if the switch 263 is moved to close contacts 266 and 267 the circuit is completed to automatic control switch 14CR-3. The switch 14CR-3 is associated with the cycle control relay 14CR in E33 and thus whenever a cycle is started the switch 14CR-3 will close and start the headstock motor if switch 263 is set for automatic operation.

The two switches 18CR-2 and 14CR-3 are connected in parallel to line 268 which is connected by parallel circuits to control relays 16CR and 17CR. A direction control switch 269 is provided in these parallel circuits so that in one position it closes contacts 270 and 271 to the forward control relay 16CR, and in the other position it closes contacts 272 and 273 to complete a circuit to the reverse control relay 17CR. The control relay 16CR has a normally closed contact 16CR-1 in series with relay 17CR to prevent its operation when relay 16CR is energized, and relay 17CR has a normally closed contact 17CR-1 in series with relay 16CR to prevent its operation when relay 17CR is energized.

Relay 16CR has a contact 16CR-2, E9, for energizing solenoid SOL13 and relay 17CR has a contact 17CR-2, E10, for energizing solenoid SOL15, both shown in Figure 10. As shown in Figure 16, these solenoids control reversible operation of the headstock motor 38.

Power for manual control of the tailstock is obtained by the closing of switch 12CRB-1, E59, when 13CRB-1, E60, is open. The relays 10CR and 9CR in E59 and E61 which control the advance and return of the tailstock have latching relays 10CR-1, E60, and 9CR-2, E62, so the timer relay 3TR in E62 is provided for operation by closure of switch 274 associated with the stop pushbutton 275. Thus, when this button is operated the timer relay will open its switch 3TR-1, E59 immediately, and its time closing will insure that the latching contacts are open in case of quick operation of the pushbutton.

The automatic operation of the machine has been described in which both tools were utilized simultaneously for forming the work. It may be desirable, however, to utilize just one tool while the other remains idle, and therefore the selector switches 121, E36, and 122, E50 were provided for making this selection.

If the front tool is to be used, the front main slide 60' and its cross slide 69' are coupled in the circuit, and the rear slides remain idle. In this case the selector switch 121, Figure 14, is rotated into position so that the switch pads 276, 277 and 278 make the necessary connections to control relays 3CR and 4CR to control reversible operation of the longitudinal slide piston 65'. In other words, the switch pad 278 interconnects contacts 130 and 131 in E44, and the switch pad 277 interconnects contacts 126 and 127 in E39. This connects the relays 3CR and 4CR to the manual control switches in E41 for manual

control when 12CRA-2 is closed or for automatic operation when 13CRA-2 in E38 is closed. Since only one set of slides is going to be controlled the limit switch 5LS associated with the other set of slides will never be closed and therefore to establish a circuit the switch pad 276 is provided for short circuiting this limit switch by interconnecting contacts 279 and 280 in line E37.

At the same time the operator adjusts the selector switch 122, Figure 15, to position the switch pads 281, 282 and 283 for making certain connections in Figure 12 to render the control relays 7CR and 8CR in E51 and E50 respectively effective to control the movements of the cross slide piston 73'. The pad 283 interconnects contacts 140 and 141, and pad 282 interconnects contacts 136 and 137 to connect the control relays for manual control by the switches in line E51 when 12CRA-3 is closed or for automatic operation when 13CRA-4 and 13CRA-5 are closed. The switch pad 281 interconnects contacts 284 and 285 in line E56 to short circuit the limit switch 1LS-2 which remains open because associated with the idle slide.

When the rear slides are to be utilized alone the selector switches 121 and 122 are rotatably adjusted in the opposite direction to render the front set of slides idle and the rear set of slides active. In this case, the switch 121, Figure 14, is provided with switch pads 286, 287, and 288. The pad 287 interconnects contacts 128 and 129, and pad 288 interconnects contacts 130' and 131' to connect control relays 1CR in E42 and 2CR in E46 for manual control by the switches in E41 when 12CRA-2 is closed, or for automatic operation when 13CRA-2 and 13CRA-3 are closed. The other switch pad 286 interconnects contacts 289 and 290 in E37 to short circuit the limit switch 8LS which is idle and remains open during this operation.

The selector switch 122, Figure 15, has switch pads 291, 292, and 293, the pad 292 interconnecting contacts 138 and 139 in E53, and the pad 293 interconnecting contacts 142 and 143 in line E57 with the result that control relays 5CR and 6CR are connected for manual control by the switches in E51 when 12CRA-3 is closed, or for automatic operation when 13CRA-4 and 13CRA-5 are closed. The pad 291 interconnects contacts 294 and 295 in line E56 to short circuit limit switch 3LS-2 which is idle during this operation.

It will be noted from Figure 13 that two pumps, 150 and 166, are provided for supplying the hydraulic circuit, and the pump 150 has the greater capacity and when the slides are not being actuated it is desirable to provide some relief for the pump rather than depending upon its relief valve 296, and so a separate bypass to reservoir has been provided comprising the channel 297 which is connected to port 298 of a bypass valve 299 having a valve plunger 300 which is shiftable in one direction by the solenoid SOL12 and in the other direction by a spring 301. A return line 302 to reservoir is connected to port 303 of the by-pass valve whereby in the normal position of the plunger 300 as established by the spring 301 the valve groove 304 interconnects the ports 298 and 303, whereby the supply from pump 150 is bypassed to reservoir. Provision is made that whenever any of the main slides or cross slides or tailstock is actuated, establishing a demand for fluid pressure the solenoid SOL-12 is actuated to shift the valve plunger 303 and disconnect the ports 298 and 303. As shown in Figure 10, the solenoid SOL12 in line E19 is connected in parallel to contacts 4CR-3, 1CR-3, 2CR-3, 3CR-3 and 10CR-3 whereby when any of the relays associated with these switches are operated the solenoid will be actuated to isolate the ports 298 and 303 and make the pump effective.

What is claimed is:

- In a spinning machine having a work forming mandrel, a bed, and a headstock and tailstock supported on the bed in operative engagement with opposite ends of said mandrel, the combination of tooling units mounted on the bed on opposite sides of said mandrel, each unit

including a power operable cross slide mounted on a power operable main slide, a spinning tool carried by the cross slide, means to adjust said units independently to align the path of movement of the main slides parallel to the taper of the mandrel on the respective sides thereof and position the spinning tool opposite the end of the mandrel, a cycle control mechanism for said slides including a cycle starting relay, a control relay for each slide, a control circuit including a cross slide branch circuit and a main slide branch circuit connected in parallel to said cycle starting relay, serially arranged limit switches in the cross slide circuit held closed by the main slides in starting position, serially arranged limit switches in the main slide circuit normally open when the cross slides are in starting position and adapted to be closed thereby upon reaching their advanced position, a first switching means for connecting both control relays for the cross slides to the cross slide circuit, and a second switching means for connecting both of said control relays for the main slides to the main slide circuit and for simultaneously bridging the serially arranged limit switches in the cross slide circuit, whereby energization of the cycle starting relay will cause advance of the cross slides, and completion of cross slide advance will cause simultaneous starting of said main slides while maintaining both control relays for the cross slides energized during movement of the main slides.

2. In a spinning machine having a work forming mandrel, a bed, and a headstock and tailstock supported on the bed in operative engagement with opposite ends of said mandrel, the combination of tooling units mounted on the bed on opposite sides of said mandrel, each unit including a power operable cross slide carrying a spinning tool mounted on the main slide, means to adjust said units on the bed to align the path of movement of the main slide parallel to the taper of the mandrel on the respective sides thereof and position the spinning tool opposite the end of the mandrel, a cycle control mechanism for said slides including a cycle starting relay, a control relay for each slide, a control circuit including a cross slide branch circuit and a main slide branch circuit connected in parallel to said control circuit, serially arranged limit switches in the cross slide circuit held closed by the main slides in starting position, serially arranged limit switches in the main slide circuit normally open when the cross slides are in starting position and adapted to be closed thereby upon reaching their advanced position, a first selector switch for connecting either one or both of the cross slide control relays to the cross slide circuit, a second selector switch for connecting either one or both of the main slide control relays to the main slide circuit whereby upon energization of the cycle starting relay either one or both of the tooling units may be selectively actuated.

3. In a spinning machine having a work forming mandrel, a bed, and a headstock and tailstock supported on the bed in operative engagement with opposite ends of said mandrel, the combination of a tooling unit mounted on the bed on opposite sides of said mandrel, each unit including a power operable cross slide mounted on the main slide, means to adjust said units on the bed to align the path of movement of the main slide parallel to the taper of the mandrel on the respective sides thereof and position the spinning tool opposite the end of the mandrel, a cycle control mechanism for said slides including a cycle starting relay, a control relay for each slide, a control circuit including a cross slide branch circuit and a main slide branch circuit connected in parallel to said control circuit, serially arranged limit switches in the cross slide circuit held closed by the main slides in starting position, serially arranged limit switches in the main slide circuit normally open when the cross slides are in starting position and adapted to be closed thereby upon reaching their advanced position, a first selector switch for connecting either one or both of the cross slide control relays to the cross slide circuit, a second selector switch for connecting either one or both of the main slide control relays to the main slide circuit whereby upon energization of the cycle starting relay either one or both of the tooling units may be selectively actuated.

slide circuit normally open when the cross slides are in starting position and adapted to be closed thereby upon reaching their advanced position, a first selector switch for connecting either one or both of the cross slide control relays to the cross slide circuit, a second selector switch for connecting either one or both of the main slide control relays to the main slide circuit whereby upon energization of the cycle starting relay either one or both of the tooling units may be selectively actuated, parallel arranged circuits to said branch circuits, a selector switch for connecting a source of power alternately to said parallel arranged circuits or to said branch circuits, and switch means in said parallel arranged circuits for manually controlling the slides individually or in pairs determinative on the setting of said first and second selector switches.

5 10 15

4. In a spinning machine having a work forming mandrel, a bed, and a headstock and tailstock supported on the bed in operative engagement with opposite ends of said mandrel, the combination of a tooling unit mounted on the bed on opposite sides of said mandrel, each unit including a power operable cross slide carrying a spinning tool mounted on the main slide, means to adjust said units on the bed to align the path of movement of the main slide parallel to the taper of the mandrel on the respective sides thereof and position the spinning tool opposite the end of the mandrel, a cycle control mechanism for said slides including a cycle starting relay, a control relay for each slide, a control circuit including a cross slide branch circuit and a main slide branch circuit connected in parallel to said cycle starting relay, serially arranged limit switches in the cross slide circuit held closed by the main slides in starting position, serially arranged limit switches in the main slide circuit normally open when the cross slides are in starting position and adapted to be closed thereby upon reaching their advanced position, a first selector switch for connecting either one or both of the cross slide control relays to the cross slide circuit, a second selector switch for connecting either one or both of the main slide control relays to the main slide circuit whereby upon energization of the cycle starting relay either one or both of the tooling units may be selectively actuated, parallel arranged circuits to said branch circuits, a selector switch for connecting a source of power alternately to said parallel arranged circuits or to said branch circuits, and switch means in said parallel arranged circuits including advance, return, and rapid traverse switches for manually controlling the slides individually or in pairs determinative on the setting of the first and second-named selector switches.
